UNITED STATES PATENT OFFICE.

ROBERT C. PARVIN, OF MOUNT HOLLY, NEW JERSEY.

AXLE-BOX.

SPECIFICATION forming part of Letters Patent No. 288,851, dated November 20, 1883.
Application filed July 31, 1883. (No model.)

To all whom it may concern:

Be it known that I, ROBERT C. PARVIN, a citizen of the United States, residing at Mount Holly, in the county of Burlington and State 5 of New Jersey, have invented certain new and useful Improvements in Axles and Axle-Boxes, of which the following is a specification, reference being had therein to the accompanying drawings.

- 10 My invention relates to certain new and useful improvements in axles and axle-boxes; and it consists in arranging a series of friction-rollers around the arm of an axle within the axle-box, which is formed with an inner enlargement, and providing said axle-box with a retaining collar and pin, and forming said rollers and axle in such a manner that longitudinal movement of the parts is to a great extent obviated.
- 15 The object of my invention is to reduce the friction in axle-bearings to the minimum, to reduce the amount of wear and grinding away of the axle and axle-box, so common in the old formation of axle and box, and prevent to 20 a great extent the sliding end motion when the axles are in use. I attain these objects by means of the peculiar construction and arrangement of the various parts of my device, which will be more fully pointed out and described in the specification and claims.

Reference being had to the drawings accompanying this application, and forming part of the same, Figure 1 is a perspective view of my invention, showing the axle and axle-box in place. Fig. 2 is a longitudinal sectional view, showing the inside of half the box and a portion of the friction-rollers. Fig. 3 is a vertical sectional view taken through the center of axle arm and box, showing position of friction- 25 rollers and central bearings. Fig. 4 is a cross-section of axle-box, showing central enlargement. Fig. 5 is a detail view of the enlargement or central open band around axle-arm.

Similar letters refer to similar parts throughout the drawings.

Referring to the drawings, A represents the axle-box, and B the axle. The axle-box is formed of metal, and of any desired length and diameter, suitable for use in any hub of a 30 wheel used on vehicles, said box being con-

structed in the form of a hollow cylinder of equal diameter on the inside from end to end, except the center, which is enlarged or thickened to form an annular ring, f, having square shoulders, the purpose of which is to form 55 bearings for friction-rollers, that are introduced endwise in said axle-box. The outer surface of said axle-box is provided with longitudinal fins or ribs a², by which said box A is held in place within the hub of the wheel. 60 The inner surface of said axle-box is formed of about the same diameter, except the center, which is raised or thickened to form a bearing, f, on which the rollers, in part, form a bearing.

The axle B, or axle-arm, I prefer to form of the same diameter from shoulder to linchpin or washer, except the central portion, which is surrounded with a collar, b', that acts partially as a bearing and partially as a stop to 70 hold friction-rollers.

Friction-rollers g (usually nine in number) are formed of metal, and of the same length as the box A, the central portion of each roller being recessed to a sufficient depth to 75 admit the annular enlargement f and the collar b, by which said friction-rollers are held in place against any end movement, the shoulders of said recesses g' acting as end bearings for said friction-rollers, whereas their outer ends have 80 bearings against the collar b and the washer c in common with the ends of the box A. By this construction the bearings on the arm of the axle are equally divided, the weight in the vehicle is equally distributed along the arm of 85 the axle, and less friction is encountered, and the wheel revolves on the bearing free and easy, whereby a greater load can be carried on the wagon than by the ordinary construction of axle and axle-box.

Axle-box B, as hereinbefore stated, may be formed in two half-sections, that, when united, form a hollow cylinder with equal internal diameter. One end may be formed closed, except a central perforation for the reception of 95 the axle. The friction-rollers g are introduced into the axle-box B by first placing them parallel in position around the spring-band b', said band fitting inside the shouldered recesses g' formed in said friction-rollers. The wheel 100

containing the axle-box B is placed in a horizontal position, so that one end of box A rests on the upper face of the base of a cone, the cone part projecting into said box, sufficient space being left between the inner face of the box and the outer surface of the cone to receive the friction-rollers g, which are dropped in from the outer end of box B. When all the rolls g are in place, the ring b' is sprung into the recesses g', and by expanding holds the rolls g against the inner face of box B, when the cone is withdrawn and the axle inserted. An opening for oil-pipe b² is made in box B, said pipe extending out through the hub of the wheel.

I am aware of the Patent No. 218,939, dated August 26, 1879, for "axle-boxes," its construction and arrangement of the various parts, and I therefore do not, broadly, claim the same. Having thus described my invention, what I claim, and desire to secure by Letters Patent, is—

1. A metallic axle-box with an inner central annular enlargement formed integrally with the box, and retained upon the axle by 25 a collar, c, and lynchpin, in combination with a series of loose or non-journaled friction-rollers extending nearly the entire length of the box, and having central recesses, substantially as shown and specified.

2. The combination of the axle-box A, the internal annular central rib, f, and the friction-rollers g, having recesses g', with the axle-arm B, having central collar, b', the washer c, and the collar b, all arranged and operated substantially as shown.

In testimony whereof I affix my signature in presence of two witnesses.

ROBERT C. PARVIN.
